TRANSMISSION LINE SUPPORT ARM

Lee J. Dake, Elmhurst, Ill., assignor to Joslyn Mfg. and Supply Co., Chicago, Ill., a corporation of Illinois

Filed Jan. 20, 1967, Ser. No. 5,504

Term of patent 14 years

(Cl. D26—12)

FIG. 3

FIG. 1 is a perspective view of a transmission line support arm showing my new ornamental design;

FIG. 2 is a front elevational view of the transmission line support arm of FIG. 1;

FIG. 3 is a side elevational view of the transmission line support arm of FIG. 1; and

FIG. 4 is a top plan view of the transmission line support arm of FIG. 1.

The rear elevational view of the transmission line support arm of FIG. 1 is identical with the view of FIG. 2, and the opposite elevational view is identical with the view of FIG. 3. The broken line showings of a support pole, an electrical insulator, and a transmission line are for illustrative purposes only.

I claim:

The ornamental design for a transmission line support arm as shown and described.
